UNITED STATES PATENT OFFICE.

DAVID BROOKS, JR., OF PHILADELPHIA, PENNSYLVANIA.

CONDUIT ELECTRIC RAILWAY.

SPECIFICATION forming part of Letters Patent No. 540,900, dated June 11, 1895.

Application filed June 9, 1892. Renewed December 7, 1894. Serial No. 531,100. (No model.)

To all whom it may concern:

Be it known that I, DAVID BROOKS, Jr., a citizen of the United States, residing in the city and county of Philadelphia, State of Pennsylvania, have invented a new and useful Improvement in Electric Railways, which improvement is fully set forth in the following specification and accompanying drawings.

The object of my invention is the formation of an electrical connection between an underground trolley wire or rail, and an electrical railway car, and consists of one or more chains, linked pieces or wires or other flexible material, which by their own weight rest upon the top of the wire or rail.

It also consists of a guard for said chains, &c., whereby a continuous contact of the latter with the wire or rail may be maintained.

It also consists in breaking the continuity of the contact of the chain, &c., with the wire or rail, for causing an automatic momentary interruption of the current, and providing the receiver with a guard, as will be herein-after set forth.

Figure 1 represents a transverse vertical section of an electrical railway embodying my invention. Fig. 2 represents a longitudinal vertical section thereof. Fig. 3 represents a perspective view of the construction of the railway at the place of crossing. Fig. 4 represents a view of the construction of the railway at a break therein.

Similar letters of reference indicate corresponding parts in the several figures.

Referring to the drawings, A designates a sub-way or conduit of suitable construction. B designates a slot in the crown or top thereof.

C designates insulators within the conduit, the same being formed of suitable non-conducting material, and supported on hangers D, which are properly secured to the conduit.

On the insulators C, are placed the electrical conductors E and F, between which is a strip G of wood or other insulating material forming together a rail, the lower conductor F being continuous, and the upper conductor E sectional or separated at intervals, as at H, Figs. 2 and 4. At the ends of the sections of said conductors E, are pieces J of fusible material, the same connecting the conductor F with the said sections, by which provision, should any material or article drop upon the

conductor E, and thus cause a short circuit, the connection J will fuse, so that only the relative section of the conductor E will be affected without injuring the remainder of the conductor. Where railways cross, the conductors are separated as shown in Fig. 3, and the ends of opposite conductors are connected by brackets K, said brackets crossing and located one below the other, so as not to interfere with each other, and serving to sustain the ends of the conductors.

L designates the piece of metal which receives the electric current, the same being connected with the car and movable through the slot B.

Depending from the piece or receiver L are several chains M, or in lieu thereof linked pieces of metal or pieces of wire which rest by their own weight freely on the top of the rail and rise and fall with said receiver and thus always remain in contact with the same, it being noticed that the electric current from the rail is taken up by said chains or pieces, and thus conducted to the receiver L. On the rail are guards N, which are preferably formed of wire, and project upwardly from the sides of the rail, and serve to keep the chains or pieces M from slipping from the rail, thus insuring a contact at all times of the chains or pieces with the rail. As the guards are separated one from another, water is permitted to run off of the rail, the effect of which is evident. It is believed to be advantageous to make a small break in the continuity of the chain contact with the rail, as at J. This will cause a momentary automatic interruption of the current and notify the driver of the car of the same, or cause a reversal of the current at dangerous points. The receiver L is guarded on opposite sides by pieces P of uninsulated metal, whereby damage to the same may be prevented.

Having thus described my invention, what I claim as new, and desire to secure by Letters Patent, is—

1. In an electric railway, an insulating support, a continuous electric conductor thereon, a sectional conductor with intervening insulating material on said continuous conductor, pieces connecting said conductors, a receiver adapted to be connected with a car, and a chain connected with said receiver and

adapted to contact with said sectional conductor, said parts being combined substantially as described.

2. In an electric railway, an insulating support, a sectional conductor and a continuous conductor with intervening insulating strips on said support, the upwardly projecting guards N on the sides of said sectional conductor, and the receiver L with the chain M, the latter adapted to contact with the said sectional conductor, said parts being combined substantially as described.

3. In an electric railway, a conduit with slot, an insulating support on hangers in said

conduit, a continuous conductor on said support, insulating strips on said continuous conductor, a sectional conductor with separated ends on said strips, pieces connecting the ends of said sections and said continuous conductors, a receiver movable in said slot, a frame protecting said receiver, and a chain secured to said receiver and in contact with said sectional conductor, said parts being combined substantially as described.

DAVID BROOKS, JR.
